FIG. 5.

UNITED STATES PATENT OFFICE.

MARCUS O. ANTHONY, OF ENGLEWOOD, AND GUSTAF A. WALLIN, OF SCOTCH PLAINS, NEW JERSEY, ASSIGNEES TO A. KIMBALL COMPANY, OF NEW YORK, N.Y., A CORPORATION OF NEW YORK.

PIN-TICKET-ATTACHING DEVICE.

1,254,017.

Specification of Letters Patent. Patented Jan. 22, 1918.

Application filed May 14, 1915. Serial No. 28,190.

To all whom it may concern:

Be it known that we, MARCUS O. ANTHONY, a citizen of the United States, and resident of Englewood, county of Bergen, State of New Jersey, and GUSTAF A. WALLIN, a citizen of the United States, and resident of Scotch Plains, county of Union, State of New Jersey, have invented an Improvement in Pin-Ticket-Attaching Devices, of which 10 the following description, in connection with the accompanying drawing, is a specification, like characters on the drawing representing like parts.

This invention relates to improvements 15 in implements for attaching pin tickets to fabrics and other lines of merchandise.

The usual form of pin ticket comprises a card *a* having a staple affixed thereto, the shanks *b* and *c* of the staple extending in 20 parallelism at right angles to the under surface of the card. In affixing such tickets to merchandise the shanks of the staple are passed through the merchandise and are bent laterally until they lie against the 25 surface thereof, the ends being preferably bent farther down toward the back of the card so that the points will not engage other goods. These pin tickets are usually applied by girls, and in bending the shanks of 30 the staple their fingers are roughened and sometimes lacerated by continuous contact with the sharp edges or burred points of the staples which are generally used in pin tickets, in which the points are formed by 35 severing the wire at an acute angle to its axis, so that it is desirable to have mechanical means for engaging, separating and clenching the staples. Certain types of apparatus have heretofore been constructed for 40 this purpose but such apparatus is ordinarily in the form of permanently located machines to which the merchandise must be brought in order to affix the pin tickets thereto. This of course is not only incon- 45 venient but occasions loss of time.

One of the objects of the present invention therefore is to provide an implement which can be readily carried by the operator and used to affix the pin tickets to the mer- 50 chandise.

Another serious objection to the use of machines for affixing tickets resides in the fact that the staples of the pin tickets are formed with cut points which frequently

have sharp edges or burs or are blunted so 55 that when they penetrate the fabric the burs or rough ends will snag or cut the material. In such case it is undesirable to force the pin through the goods. In machine work, of course, no discrimination is made between 60 perfect and imperfect pin tickets and goods are frequently damaged by the application of these defective pin points.

A desirable feature of the present invention is that in utilizing the implement forming the subject matter of this invention, pin tickets are inserted in the usual manner and if the operator finds a bur upon the pin or any other obstruction which makes it difficult to thrust the pin through the goods the 70 ticket may be discarded and damage to the goods avoided.

Another object of the invention is to provide a device of the character above described which will force the shanks of the 75 tickets more firmly against the merchandise to which the ticket is applied than is usually done by hand so that the points of the staple will be prevented from snagging other folds of the same fabric or other merchandise 80 which may come in contact with the pin ticket.

A preferred form of the invention is disclosed in the accompanying drawings in 85 which,

Figure 1 is an enlarged front elevation of the pin ticket clenching implement carried by the finger of an operator and in normal position and engaging the ends of a pin ticket about to be affixed,

Fig. 2 is a similar view showing the device when forced downwardly by the finger of the operator so as to separate and clench the shanks of the staple upon the fabric,

Fig. 3 is an enlarged side elevation of the 95 device engaging the pins of the staple and showing the groove which directs the shank of the staple as it is being clenched,

Fig. 4 is a vertical sectional view of the device,

Fig. 5 is a vertical sectional view through one of the clenching members, and,

Fig. 6 is a perspective view of a pin ticket of the usual type.

As illustrated in Figs. 1 and 2 of the 105 drawing the implement for clenching the pin tickets is shown as applied to the finger of an operator, the pin ticket resting upon

the surface of a table. In Fig. 1 the device is shown as approaching the pin ticket and in Fig. 2 after the same has been thrust down to expand and clench the staple.

These illustrations of the use of the pin ticket clenching implement in connection with a table are merely for the purpose of illustrating the extent of movement of the clenching members relatively to the plane of the ticket since it will be readily understood that in ordinary use the pin ticket and merchandise will be supported by the finger of the operator rather than by a table or other rigid support, although it is perfectly feasible to attach tickets in the manner illustrated.

The preferred embodiment of the invention disclosed in the drawing comprises a supporting member 1 which preferably is in the form of a thimble adapted to be worn upon the finger of the operator and a pair of clenching members 2-3 flexibly connected, preferably by a hinge 4. The clenching members are supported upon the thimble by arms 5 and 6 which pass through suitable guides 7 and are connected at their ends to the thimble by hinges 8. The arms are flexibly connected at their lower ends to the backs of the clenching members 2-3 in any suitable manner.

These clenching members may conveniently be constructed of two similar plates 10 having complementary hinge portions 11-11 at their adjacent ends and an upwardly bent rib 12 adapted to receive the pintle 13 extending through eyes 14 in a yoke shaped end 15 of the arms 5-6, the front of the clenching members consists of an attached plate 16 having a groove 17 converging outwardly from the hinge 4. Springs 18 preferably surrounding the pintles 13 of the hinges 9 and having ends engaging respectively the rear faces of the clenching members and the inner faces of the arms 5-6 serve normally to maintain the clenching members in contracted position, in which they are disposed in angular relation to one another so as to present an apex adapted to be thrust between the shanks of the staple of the pin ticket.

Since the shank engaging plate 16 is provided with a groove 17 converging upwardly from the hinge 4 the ends of the shanks will be guided in opposite directions and the bent shanks of the pin will lie substantially parallel to the upper edge of the ticket. By thus bending the shanks uniformly there is no danger of the sharp point projecting beyond the end of the pin ticket in such a manner as to engage other merchandise or to scratch those handling the goods.

In the operation of the device the staple of the pin ticket is passed through the goods by the operator and the clenching imple-

ment is then projected between the points of the staple of the pin ticket in the manner illustrated in Fig. 1, the converging ends of the clenching members 2 and 3 being thrust between the shanks *b* and *c* so that the pins of the staple enter the guiding grooves 14, the operator then presses down upon the thimble causing the shanks *b* and *c* to be separated. When the hinge 4 abuts against the merchandise which lies upon the reverse face of the card *a* the shanks spread as further pressure is applied by the finger of the operator until the faces 16 of the clenching members are in the same plane. Further pressure upon the clenching members changes the fulcrum of the clenching members from the hinge 4 to the angularly bent portions 15 of the staple, resulting in the forcing of the ends of the staple firmly against the face of the fabric to which the pin ticket is being attached, as clearly illustrated in Fig. 2. By thus changing the fulcrum of the clenching members from the hinge to the bent portion 15 of the staple—rather than by curving the clenching members—the pressure of the clenching members is applied to the body of the staple and not to the extreme point so that the danger of bending the point into the form of a hook which would snag or cut the fabric upon withdrawal of the pin is avoided.

While we have illustrated the invention as comprising a thimble adapted to be applied to the finger of the operator it will be obvious that other forms of supporting members may be used and that various modifications in construction of the device may be made, and that the same may be adapted for other uses within the spirit and scope of the following claims.

Having thus described our invention what we claim as new and desire to secure by Letters Patent is:

1. A device of the class described comprising a supporting member, a pair of flexibly connected clenching members, and means attached to said supporting member and to said clenching members adapted normally to maintain the clenching members in contracted relation and operable by pressure upon said supporting member to expand said clenching members.

2. A device of the class described comprising a supporting member, a pair of flexibly connecting clenching members, and oppositely disposed arms hinged to said supporting member and to said clenching members adapted normally to maintain the clenching members in contracted angular relation to each other and operable by pressure upon said supporting member to expand said clenching members to the same plane and by continued pressure to reverse the angular relation therebetween.

3. A device for clenching the staples of

pin tickets comprising a thimble, a pair of flexibly connected clenching members, and means connecting said thimble and clenching members and operable to expand said 5 clenching members upon engagement of the latter with the shanks of the staples.

4. A device for clenching the staples of pin tickets comprising a thimble, a pair of clenching members having converging guid- 10 ing grooves extending upwardly from said hinge, and spring actuated means connecting said thimble and said clenching members adapted normally to maintain the clenching members in contracted angular 15 relation to each other and operable by pressure upon said thimble to expand said clenching members upon engagement of the latter with the shanks of the staple.

5. A device for clenching the staples of pin 20 tickets consisting of a finger thimble, a pair

of flexibly connected clenching members, op- 25 positely disposed arms hinged to said thim- ble and said clenching members, and springs carried by the hinges connecting the arms to the clenching members adapted normally to retain the clenching members in contracted 30 angular relation to each other so as to pre- sent diverging staple engaging surfaces, whereby pressure applied to the thimble upon engagement of said clenching mem- 35 bers with the shanks of the staple will cause first expansion of the clenching members and thereafter reversal of the angular relation of the same to press the ends of the staple firmly against the article to which the ticket is affixed.

In testimony whereof, we have signed our names to this specification.

MARCUS O. ANTHONY.
GUSTAF A. WALLIN.
